(57) CLAIM

The ornamental design for an electronic camera, as shown and described.

DESCRIPTION

FIG. 1 is a top, front and side perspective view of an electronic camera showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a side elevational view thereof from the left of FIG. 2, the appearance of the side opposite that shown in FIG. 6 being identical thereto.
